CLAIM

The ornamental design for a trail camera weather guard, as shown and described.

DESCRIPTION

FIG. 1 is a perspective view of the trail camera weather guard of my new design showing it protecting a trail camera, shown in broken lines.

FIG. 2. Is a front elevational view thereof.

FIG. 3 is a back elevational view thereof.

FIG. 4 is a side elevational view thereof.

FIG. 5 is an elevational view of the side opposite to that of FIG. 4.

FIG. 6 is a top plan view thereof; and,

FIG. 7 is a bottom plan view thereof.

The broken line element in FIG. 1, depicting a trail camera situated underneath the trail camera weather guard of my new design, is an environmental element, and forms no part of my new design.

1 Claim, 6 Drawing Sheets
